FIGURE 1 is a perspective view of an adjustable handle file frame or the like, showing my new design;

FIGURE 2 is a side elevational view thereof, with the opposite side not shown being of similar appearance;

FIGURE 3 is a fragmentary side elevational view thereof showing one of either of the movable knobs in an alternative position;

FIGURE 4 is a top plan view, partly in section, the section being taken approximately on the plane of the line 4-4 of FIGURE 2;

FIGURE 5 is a bottom plan view of the device;

FIGURE 6 is an end view thereof on a slightly larger scale, taken from the right hand end of FIGURE 2; and

FIGURE 7 is an end view thereof also on a slightly larger scale, taken from the opposite or left hand end of FIGURE 2.

I claim:

The ornamental design for an adjustable handle file frame or the like, substantially as shown and described.
